UNITED STATES PATENT OFFICE.

GEORGE M. KUHN, OF ST. LOUIS, MISSOURI.

MERCHANTISE-VENDING MACHINE.

Application filed July 21, 1920. Serial No. 397,986.

To all whom it may concern:

Be it known that I, GEORGE M. KUHN, a citizen of the United States, residing in the city of St. Louis and State of Missouri, have 5 invented certain new and useful Improvements in Merchandise-Vending Machines, of which the following is a specification.

My invention relates generally to mechanisms adapted to the vending of most any 10 class of articles of general merchandise and is a distinct and practical improvement to overcome certain important practical objections to, and defects in, the universal type of vending machine.

15 The object of my invention is to provide a mechanism which, by duplication, shall be adapted to vend an unlimited number of articles of general merchandise accurately, more economically and with much less manual labor than has been possible hitherto.

Another object of my invention is to provide a mechanism which shall be adapted to vend a very large number of different articles of merchandise directly to the purchaser without the intervention of the seller or of clerks and cashiers in effecting the 25 sale and delivery, and receipt of the purchase price, of the articles desired by the purchaser.

30 A still further object of my invention is to provide a device for vending merchandise which will be simple and comparatively inexpensive in construction, easily and quickly actuated for delivering goods to a position 35 from which the vendee can remove the same from its supporting shelf at the time of purchase and which will prove itself highly efficient for the purpose intended.

With the above and other objects in view, 40 the invention consists in the novel construction, arrangement and combination of parts hereinafter described and finally pointed out in the claims hereto appended.

45 Referring to the accompanying drawings forming a part of this specification wherein like characters of reference denote similar parts throughout the several views:

Fig. 1, is a front elevation of one complete unit of my improved merchandise vending machine.

Fig. 2, is a rear elevation thereof.

Fig. 3, is a top plan view thereof with portions thereof broken away and portions shown in cross-section.

Fig. 4, is a plan view of the coin controlled actuating mechanism. 55

Fig. 5, is a view taken on line 5—5 of Fig. 4.

Fig. 6, is a detail, showing a coin moved to a position to be discharged. 60

Fig. 7, is a detail, similar to Fig. 6, with coin discharged and the several parts of mechanism in position as having actuated the table releasing dog, or lever.

Fig. 8, is a rear elevation of the hand 65 wheel, showing the cams fixed thereto.

Fig. 9, is a plan view of the hand wheel, partly in section and partly in elevation, clearly showing the cam and push rods.

Fig. 10, is a plan view of a unit of the 70 merchandise vending machine, showing a shelf provided with a multiplicity of merchandise receiving compartments for small articles.

Fig. 11, is a detail, clearly showing the 75 ratchet-band fixed to one of the shelves of the unit.

Fig. 12, is a sectional view taken on line 12—12 of Fig. 3, looking in direction of the arrow. 80

Fig. 13, is a detail of the interchangeable coin receiving member.

Fig. 14, is a detail of the coin engaging member.

In carrying out the aim of my present 85 invention, I employ a plurality of merchandise supporting tables, or shelves designated 1, 2, 3, 4, 5, 6, 7, 8, 9, and 10. Each table is provided with a sleeve 11 and is rotatably supported by means of a central 90 arranged supporting post 12, as clearly shown in Figures 2 and 3. The post, or standard 12 is suitably fixed to the floor so that it is held stationary.

Each revolving merchandise supporting 95 table is provided with a housing 13 suitably fixed to the upper face thereof. A suitable flat coiled spring 14 is arranged in each housing 13 and fixed at its inner end to the supporting post 12 and at its outer end to 100

the spring housing 13 so that the unwinding of the spring will revolve its respective table.

The merchandise supporting tables are positioned behind suitable walls, designated 15 and 16. These walls are spaced apart at their inner edges to provide a package discharge opening, or passage 17. The wall designated 16 is preferably provided with a 10 glass panel 18 so that the purchaser may observe the goods to be purchased.

Each merchandise supporting table is provided with a plurality of partitions 19 radiating outwardly from the spring housing 13 to provide individual merchandise receiving compartments 20, as shown in Figures 3 and 10. 21 indicates merchandise, or goods, in package form, arranged in the compartments 20 of a merchandise 20 supporting shelf. The compartments 20 are of a width at their outer ends equal to the width of the discharge opening 17, as shown in Figure 3. The front compartment is not provided with merchandise, as shown in 25 Figure 3. When the compartments 20 are smaller at their outer ends than the width of the discharge opening 17, as shown in Figure 10, a plurality of compartments 20 are free of merchandise, as shown. From 30 the foregoing, it is evident that any desired number of merchandise receiving compartments 20 may be employed for each revolving merchandise supporting table.

Each revolvable merchandise supporting 35 table is provided with a peripheral band 22 provided with the inclined faces 23 and stops 24. The stops 24 are positioned directly below the outer end of each compartment partition 19 so that the table can 40 only revolve a distance equal to the width of the outer open end of the merchandise receiving compartments. The stop band 22 is interchangeable and can be removed, when desired, to provide a table with a band 45 with more or less stops 24. The stop band 22 is held in position by means of suitable screws 25, or other suitable fastening devices. The partitions 19 may be removable and may be removably fixed to the upper 50 face of the merchandise supporting tables in any suitable, or well known manner.

As shown in Figure 3, 26 designates side partitions, or walls. It is evident that each vertical series of merchandise supporting 55 tables act as a unit, and as many of these units may be placed side by side, as desired, thus economizing in floor space, as the merchandise shelves, or tables are arranged one above the other and adapted to revolve independent of each other to bring the goods purchased from any shelf to a position right in front of the purchaser, where the article purchased is then removed from its compartment by the purchaser.

The compartments 20 of the tables, or 65 shelves are filled from the rear, and each time the shelves are filled, the table is revolved in a direction reverse to its delivery direction for rewinding the spring 13, which spring rotates the table when it is 70 released by the actuation of certain mechanism after a coin of the required denomination has been deposited in a coin controlled device by the purchaser.

The merchandise supporting table actuating mechanism and operation thereof will 75 now be described.

The coin controlled table actuating mechanism consists of a housing 27 having a removable top plate 28.

1', 2', 3', 4', 5', 6', 7', 8', 9' and 10' indicate dog releasing members slidably mounted in the cross-pieces 29 and 30 of the housing and are each provided with a stop shoulder 31 adapted to normally engage the cross-piece 30. Each dog releasing member is encircled by means of a suitable coiled spring 32 adapted to yieldingly hold each dog releasing member in its normal, or advanced position, as clearly 90 shown in Figures 4 and 5.

The dog releasing members 1', 2', 3', 4', 5', 6', 7', 8', 9' and 10' are connected by means of cables 32, 33, 34, 35, 36, 37, 38, 39, 40 and 41, respectively, to the shelf or 95 table releasing dogs, or levers 1'', 2'', 3'', 4'', 5'', 6'', 7'', 8'', 9'' and 10'', respectively, which levers are each pivotally supported at one end to the inner face of the front wall 15, as clearly shown in Figure 2. The 100 cables 32 to 41, inclusive, it will be observed, from Figures 4 and 5, first pass over suitable pulleys 42 and then over pulleys 43 for retaining the cables in certain paths of travel.

Each table releasing dog, or lever 1'' to 10'', inclusive, is provided with an upwardly extending lip 44 adapted to engage one of the stops 24, of each of the stop bands 22, to prevent movement of the merchandise supporting tables until the dog or lever controlling some particular shelf, or table has been withdrawn from engagement with a stop 24 of the ratchet band thereof after a coin has been deposited in the coin 115 device and the device manually actuated by the purchaser.

The coin controlled device will now be described.

The coin controlled device consists of a 120 cross-piece 45 supported at each end by the housing 27. An interchangeable coin receiving member 46 is receivable in a socket 47 in the cross-piece 45 and the member 46 is provided with a suitable coin receiving 125 passage 47' provided with a shoulder 48, as shown in Figure 12 to stop a coin of the proper denomination, and, to cause a coin

of a smaller diameter to continue traveling until it is returned to the depositor by passing directly into the passage 49 which starts from the lowest corner of the coin stop 5 shoulder 48.

As shown in Figures 4 and 5, the cross-piece 45 is provided with an opening or passage 50 adapted to receive a preferably cylindrical coin engaging member 51 having 10 a plunger receiving slot 52. The coin engaging member 51 is connected at its outer end to a movable track member 53, which track member is slidably supported at each end in the ways 54. An indicator member 15 55 is slidably mounted upon the track member 53 and is guided by means of a guide rod 56 which passes therethrough and supported at its ends by the track member 53. The indicator member 55 is provided with a rearwardly extending arm, or ram 57 adapted to be moved into alignment with one of the movable members 1' to 10', inclusive, at a time, for contact therewith when moved rearwardly, as will be fully set forth herein- 20 after.

A handle 58 extends upwardly from the indicator member 55 and passes upwardly in the top plate 28 of the housing 27. Extending at a right angle to the slotted opening 59 are the parallel arranged handle receiving slots 1", 2", 3", 4", 5", 6", 7", 8", 9" and 10", which permit movement of the track member 53 when pressure is exerted 35 thereagainst.

Extending forwardly from near each end of the track member 53 and fixed thereto at their rear ends, are a pair of opposed push rods 60 which rods are supported in the bearings 61 and 62. Each push rod 60 is provided with a stop collar 63 and a coiled spring 64 encircling each push rod between the bearings 61 and 62 and the stop collar 63, as clearly shown in Figure 4. The coiled 40 springs 64 hold the push rods 60 in their forward or normal position, as is manifest.

65 indicates a pair of push rods supported by means of the bearings 66 and 67. Each push rod is provided with a stop collar 68 and a coiled spring 69 encircling each push rod between the bearings 66 and the stop collar 68. The push rods 65 are each connected at their rear end by means of a cross-head 70. A suitable plunger 71 is centrally 50 fixed to the push rod cross-head 70 and is receivable in an opening 72 of the cross piece 45 and a registering opening 73 in the coin receiving member 46. When there is no coin in the coin receiving member 46, the plunger 55 60 71 is free to enter the slotted opening 52 of the coin engaging member 51 if forced rearwardly due to any cause, and by so freely entering the slotted opening 52 would prevent the movement of the coin engaging member which otherwise would actuate the

indicator supporting track and cause the arm 57 to engage and actuate one of the dog releasing members which would actuate a table releasing dog or lever which controls the movement of a certain merchandise supporting table. 70

The means employed for actuating the push rods 65 and plunger blade 71 to a predetermined position, then releasing same, and then continuing the movement of the 75 push rods 58 only when a coin has been deposited, consists of a hand wheel 74 having an actuating handle 75. The hand wheel 74 is provided with a peripheral flange 76 and is fixed to the outer end of a supporting 80 shaft 77 which is journaled in the bearing 78. Fixed to the inner face of the hand wheel 74, as illustrated in Figure 8, are a pair of semi-circular inner cams 79 each having the gradually inclined cam face 80 85 which terminates in a flat face 81 that terminates abruptly to establish stops 82 at one end of each cam. Also fixed to the inner face of the hand wheel 74 are a pair of three-quarter circular cams 83 each having 90 the gradually inclined cam face 84 terminating abruptly, as at 85, to form a stop face. The inclined faces of these latter cams do not start flush with the inner face of the hand wheel 74, as do the inclined cam faces 95 of the cams 80, but they commence at a suitable elevation from the face of the hand wheel, as clearly shown in Fig. 9, to provide a stop face 86 at the forward end of the inclined cam faces, to prevent more than a partial forward movement thereof unless a coin 100 of the proper denomination has been deposited in the slot of the coin receiving member 46.

As clearly illustrated in Figures 8 and 9, the forward ends of the push rods 60 and 65, are adapted to normally engage the inner face of the hand wheel. The inner push rods 65 are arranged to ride upon the cam faces 80 of the cams 79, while the outer push rods 110 58 are arranged to ride upon the cam faces 84 of the cams 83.

The operation of the merchandise vending machine is as follows:

As an illustration, we will assume that the 115 purchaser is desirous of purchasing an article of merchandise located in a compartment on shelf, or turn table designated 6.

The purchaser first moves the indicator 55, through the medium of the upright handle 120 58, to a position so that the handle 58 will register with slotted opening 6", as shown in Fig. 3. This manipulation brings the ram member 57, of the indicator member 55, in register and longitudinal alignment with 125 the dog releasing member 6", as is manifest.

After the indicator has been set, the purchaser drops a coin of the proper denomination into the coin receiving slot of the top plate 28, of the housing 27.

After the coin has been deposited, it rolls to a position in front of the coin engaging member 51 and to the rear of the plunger member 71, as shown in Fig. 5.

5 Now, the purchaser, turns the cam wheel 74 one complete revolution, by means of the handle 75.

The following actions take place during the complete revolution of the cam wheel for 10 releasing the turn table 6 and bringing the goods purchased directly before the purchaser, namely:

Just as soon as the cam wheel 74 is started in its rotary movement, the forward ends of 15 the inner push rods 65 engage the inclined faces 80 of the cams 79 forcing the plunger 71 into contact with the deposited coin. As the cam wheel is revolved, it is evident that 20 the coin and plunger 71 moves the coin engaging member 51, the indicator 55 and indicator supporting means 53 including outer push rods 58, rearwardly until the free end of ram 57 engages the forward end of dog releasing member 6", as clearly shown in 25 Fig. 6. At this position the inner push rods 65 have come to the end of the inclined faces 80 of cams 79 and instantaneously disengage the cams 79 causing the coiled springs 69 to return the inner push rods 65 and plunger 30 71 to their normal position, which movement releases the engagement of the coin with coin engaging member and the end of plunger permitting the coin to be discharged by the force of gravity through the opening in the 35 bottom wall of the cross piece 45. It will be observed, that these actions have all taken place within the first one-half revolution of the cam wheel.

The outer push rods 60 are continued in 40 their rearward movement as the cam wheel is revolved beyond one-half turn due to the forward ends of the push rods 58 having been brought into contact with the inclined faces 84 of the cams 83 through the movement of 45 the coin engaging member 51 and indicator supporting member 53. Continued rotary movement of cam wheel 74 beyond one-half revolution to the completion of one revolution causes the push rods 60 to move the ram 57 rearwardly, which in turn moves the dog releasing member 6" from its normal position shown in Fig. 5 to its rearward position shown in Fig. 7. The rearward movement of the dog releasing member 6" by 50 drawing the connecting cable gradually releases the lip 44 of the dog 6" from engagement with a stop shoulder 24 of the ratchet band 22 which is removably fixed to the peripheral face of the merchandise supporting 55 table 6.

At the completion of one revolution of the cam wheel 74, the lip 44 of the dog 6" will have been released from contact with the stop shoulder 24 through the medium of the 60 cable 32, and, just as soon as the lip has

been disengaged from the stop shoulder 24, the coiled spring 14 will revolve the table 6 a distance equal to the space of one merchandise compartment 20 to bring the goods in the compartment directly in front of the purchaser, so that the same may be removed from the table compartment by the purchaser, through the opening 17, as is manifest. Simultaneously with the movement of table 6, the outer push rods 60 disengage the 70 cams 83 causing the coiled springs 64 to instantaneously return the push rods 60 to their normal position, thus returning the indicator supporting member 53, coin engaging member 51, indicator 55 and ram 57 back to 75 their normal positions. Simultaneously with the return movement of the aforesaid members, it is evident that the coiled spring 44' will return the dog releasing member back to 80 its normal position, thereby slackening the 85 cable 37 to permit the coiled spring 44' to force the lip 44 of the dog 6" into contact with the inclined plane 23 of the ratchet band 22 to engage the succeeding stop 24, thereby 90 limiting the movement of the selected table 95 6 to a distance equal to the distance between stop 24, which distance is the width of one merchandise compartment 20 at its outer end.

Where the price of certain merchandise is different, or less, than the denomination of 95 the coin that must be placed in the coin receiving slot, the purchaser will find the correct change in the compartment upon the shelf with the goods purchased.

Should the cam-wheel, for any reason be 100 given a turn before a coin of the proper denomination has been deposited, the cam wheel can only be turned a partial revolution because the shoulder 86 of the cams 83 will engage the ends of the outer push rods 58, 105 owing to the fact that the plunger freely entered the plunger receiving slot 52 of the coin engaging member 51 which prevents a rearward movement of the engaging member 51 and the outer push rods 60 in unison 110 with the inner push rods 65, as is manifest.

Further, should a coin of a less diameter than the slot is designed to receive and retain be dropped into the coin receiving slot, 115 48, directly in front of the coin engaging member 51 and plunger 71, but the coin will roll through passage 49 and be returned to the purchaser.

To prevent reverse movement of any one 120 of the rotatable merchandise supporting shelves by a customer, or other party in front of the device, I provide each ratchet-band 22 with the same number of suitable stops 87 as there are stops 24 and in the same 125 spaced relation. A suitable dog 88, pivoted as at 89 to the end of an arm 90, is adapted to engage the stops whenever they come in contact therewith, as clearly shown in Fig. 3. The arms 90, are suitably fixed to the 130

wall 26 and the dog 88 for each arm 90 is preferably held in its proper position by means of a suitable spring 91. It will be observed, that by this arrangement, a party in 5 front of the vending device cannot impart a reverse movement to the shelves, but by releasing the dogs 88 a party refilling the shelves may reverse the shelves, which, at the same time rewinds the coiled power 10 spring to the shelf being revolved in a reverse direction.

The many advantages of the herein described invention will readily suggest themselves to those skilled in the art to which it 15 appertains.

I do not wish to be understood as having limited myself to the specific details of construction shown and described, but desire to have it understood that the invention I 20 have shown in the drawings is merely illustrative, as it is manifest that various minor changes may be made in the exact construction and particular arrangement of several parts without departing from the spirit of 25 my invention, hence I reserve the right to make any such changes, or modifications as may fairly fall within the scope of the appended claims when fairly construed.

What I claim is:

1. In a merchandise vending machine, in combination, a self rotatable merchandise supporting shelf having a plurality of compartments for receiving merchandise to be vended, a wall having an unobstructed merchandise dispensing opening arranged in advance of said shelf, said shelf having a peripheral band provided with an inclined face and a stop for each shelf compartment, a releasing dog pivotally connected to the 40 inner face of the wall having its free end engaging one of the stops of said peripheral band to prevent rotation of the shelf in one direction, means for yieldingly holding said releasing dog in contact with the stop, means 45 for releasing said releasing dog from contact with its respective stop to permit the partial rotation of the shelf to bring the succeeding shelf compartment in register with the merchandise dispensing opening in 50 the wall to permit removal of the merchandise therein to be removed therefrom by the purchaser thereof, and means to prevent reverse rotation of the shelf.

2. In a merchandise vending machine, in combination, a self rotatable merchandise supporting shelf having a plurality of compartments for receiving merchandise to be vended, a wall having an unobstructed merchandise dispensing opening arranged in 60 advance of said shelf, said shelf having a peripheral band provided with an inclined face and a stop for each shelf compartment, a releasing dog pivotally connected to the inner face of the wall having its free end 65 engaging one of the stops of said peripheral

band to prevent rotation of the shelf in one direction, means for yieldingly holding said releasing dog in contact with the stop, a dog releasing member, resilient means for holding said dog releasing member in normal position, a connection between said dog releasing member and said releasing dog, a ram normally spaced from one end of said dog releasing member in register therewith, 70 said ram being mounted for movement into contact with the dog releasing member for moving the same to actuate the releasing dog through the connection between the dog releasing member and releasing dog for releasing the shelf against movement permitting the succeeding compartment of the shelf to move into register with the merchandise dispensing opening in the wall so that the merchandise in the said shelf compartment may be removed by the purchaser 80 thereof.

3. In a merchandise vending machine, in combination, a self rotatable merchandise supporting shelf having a plurality of compartments for receiving merchandise to be vended, a wall having an unobstructed merchandise dispensing opening arranged in advance of said shelf, mechanism to prevent rotation of said shelf in one direction, locking means to prevent rotation of the shelf 95 in the opposite direction, a releasing member, resilient means acting against said releasing member, a ram spaced from the releasing member opposite one end thereof and coin controlled mechanism for actuating said ram and releasing member for releasing the merchandise supporting shelf for partial rotation to bring a succeeding shelf compartment into register with the merchandise dispensing opening of the wall.

4. In combination with a wall having a free dispensing opening therein, of a rotatable shelf having compartments for receiving merchandise positioned to the rear of said wall so that one of its merchandise receiving compartments will at all times stop to register with the dispensing opening in the wall rendering merchandise thereon removable therefrom, a stop fixed to the shelf for each compartment, a dog pivotally connected at one end to the wall and engaging a stop at its free end to prevent casual movement of the shelf, a spring for holding the free end of the dog in contact with the stop, a dog releasing member, a connection between said dog releasing member and said dog, a ram in advance of said dog releasing member and coin controlled mechanism for actuating said ram for releasing the dog to permit partial rotation of the merchandise 115 shelf to bring a full compartment to its discharge position in register with the dispensing opening of the aforesaid wall.

5. In a merchandise vending machine, in combination, a stationary central post, a se- 130

ries of spring actuated merchandise supporting shelves mounted to rotate around said post, one above another in one direction, and susceptible of co-ordination with adjacent 5 series of shelves, each shelf having a plurality of compartments open at one end for merchandise to be vended, a wall having a free dispensing opening arranged in advance of said series of shelves and extending from 10 the lower shelf to the uppermost shelf affording full view and free access to the compartment of merchandise of any shelf in register with the opening in said wall, a changeable peripheral band for each shelf 15 provided with an inclined face and a stop on the lower edge of said band for each shelf compartment to prevent the movement of the shelf in one direction, a corresponding stop on the peripheral face of the band, a 20 dog engaging said stop to prevent movement of the shelf in a reverse direction, a series of dogs pivotally connected to the inner face of the wall in such relation to the series of shelves that the free end of each dog engages 25 one of the stops on the lower edge of its re-

spective peripheral shelf band, means for yieldingly holding each dog in contact with its respective stop, a series of yieldable dog releasing members, a connection between each dog and with one of the series of dog 30 releasing members, and a ram slidably mounted to permit exact register with any one of the series of dog releasing members and a ram mounting actuated by any suitable coin controlled or other device producing a forward and backward movement, which movement propels the ram against the releasing member connected with the dog locking the shelf containing the merchandise selected by the purchaser, causing said 35 dog to unlock said shelf, permitting the same to revolve in a forward direction until the succeeding compartment is in register with the unobstructed opening in the wall and the removal of the selected merchandise 40 therefrom by the purchaser.

In testimony whereof, I have hereunto signed my name to the specification.

GEORGE M. KUHN.
